UNITED STATES PATENT OFFICE

EDWIN RUDOLPH GROTE, OF WIMBLEDON, LONDON, ENGLAND

ELECTRIC INCANDESCENT LAMP AND HOLDER THEREOF

Application filed September 18, 1930, Serial No. 482,886, and in Great Britain October 9, 1929.

This invention relates to electric incandescent lamps of the kind in which a filament is extended longitudinally of an elongated tubular body well into the substantially 5 hemi-spherical ends thereof, the lamp caps being disposed laterally of the body, so that the filaments of adjacent lamps may be brought more closely together when the lamps are arranged in line within a channel 10 or like shaped reflector or lamp holder.

The object of the present invention is to provide an improved construction of such lamps and of holders therefor.

According to this invention the lateral 15 lamp caps are so formed that they may be engaged with contact devices arranged in the lamp holder to hold the lamps in the correct position and prevent accidental falling out thereof.

20 For example the holder may be provided with contact sockets or their equivalent adapted to receive the lamp caps and means such as spring clips or locking members may be provided to retain the lamp caps in the 25 sockets or the like, the caps being suitably shaped to permit of a positive engagement with the locking members and sockets.

Means may be provided whereby the grip 30 on the contacts is first released before the lamp is withdrawn.

Provision is also made in the contact devices to allow for longitudinal expansion of the lamp bodies.

35 One construction of the improved lamp and holder will now be more particularly described with reference to the accompanying drawing, wherein:—

Fig. 1 is a front elevation of a portion of a holder showing two lamps secured in the 40 operative position therein.

Fig. 2 is a transverse section thereof, drawn to a larger scale, partly in elevation.

Fig. 3 is a longitudinal section of the holder, taken on the line 3—3 of Fig. 2, showing 45 some parts broken away, and

Fig. 4 is a fragmentary transverse section taken on the line 4—4 of Fig. 3.

Fig. 5 is a diagrammatic drawing, showing the circuit employed.

50 As shown in Figs. 1 and 2, each of the

lamps comprises a tubular glass body 1 with hemi-spherical ends 2 and a filament 3 extended well into the ends 2 and supported at intervals along its length by wires 4 projecting from a common longitudinally extending glass or other suitable rod or tube 5 suitably supported within the tubular body 1.

The wires conducting current to the filament are led out of the lamp to lateral lamp caps or bases 6 suitably secured on the seal points 7 through which the said wires pass.

As the lamps are especially intended for concealed lighting purposes they are arranged in line within a reflector 8 of substantially channel section. As will be seen from Figs. 2 to 4 this reflector is formed with a longitudinally extending channel section depression 9 within which are accommodated the contact devices adapted to engage the lamp caps 6 for the purpose of supplying current thereto and securing them in the reflector 8.

Each contact device, as shown more clearly in Fig. 3, comprises an elongated rectangular block 10 of insulating material formed adjacent one end with an elongated recess 11 and adjacent the other end with a circular recess 12.

The dimensions of the recess 12 are such that a lamp cap 6 may be inserted therein easily with a little play while, in the case of the recess 11, the dimensions are such that a lamp cap 6 be inserted therein with but slight play transversely of the reflector 8 and with a larger though limited amount of play longitudinally of the reflector.

This longitudinal play allows for expansion taking place in the lamp bodies, as will be understood, the contact devices being suitably spaced apart in the channel 9 so that one lamp cap of each lamp is engaged in a recess 12 and the other lamp cap is engaged in a recess 11 (see Fig. 1).

In order that the lamp caps may be securely held in the socket recesses 11 and 12, the block 10 of insulating material is recessed longitudinally in its upper or outer surface, as shown at 13, to receive a wire spring catch member 14 adapted to extend across the

openings to the recesses 11 and 12 and engage resiliently with a circumferential groove 15 formed in the lamp cap 6. The end 16 of the lamp cap is preferably of conical formation to facilitate the insertion of the cap into the recess 11 or 12, the conical surface 16 forcing the spring member 14 out of the path of the cap during this operation.

- 10 The spring member 14 is accommodated near its centre in the groove 17 in the upper surface of a cylindrical contact stud, 18 to the underside of which one of the current conducting leads 19 is connected by means of a 15 binding screw 20. These leads 19 are disposed longitudinally in the bottom of the channel 9 being accommodated in grooves 21 formed on the edges of the blocks 10 at the points where the latter are arranged in the 20 channel 9.

A metal plate 22 is secured by means of a screw 23 (Fig. 3) in a recess in the block 10, to cover the spring member 14, being in electrical contact with the stud 18 and formed 25 with apertures 24 and 25 corresponding in shape and position with the recesses 11 and 12 respectively.

In order to protect the contact devices and to impart a finished appearance to the reflector 8 a channel section member 26 is secured in the mouth of the channel 9 (as shown in Figs. 2 and 4) and an insulating strip 27 is disposed between the inner surface of said member 26 and the plate 22 to insulate these 30 parts from one another. This insulating strip 27 is preferably secured to the member 26 so that removal of the latter from the reflector 8 exposes the contact devices for purposes of inspection or repair. It will be 35 understood that the channel section member 26 and the insulating strip 27 are suitably apertured where they register with the recesses 11 and 12.

The spring catch member 14 preferably 40 bears on the shank of the screw 23, as well as on the wall of the groove 17 in the contact stud 18, so that the terminal portions of the spring member 14 are supported sufficiently firmly while being resiliently displaceable when lamp caps are inserted in the 45 openings 24, 25 of the metal contact plate 22.

As shown in Fig. 3 the ends of the spring member 14 are preferably bent substantially at right-angles to bear against the wall of 50 the recess 13 in the block 10 and maintain the correct positions of those portions of the spring which extend across the openings 24 and 25.

It will be seen that the insertion and removal of the lamps in or from the holder or reflector is but a simple operation, while the spring catch members prevent accidental displacement of the lamps from the holder due to their positive engagement with the lamp 60 caps.

Any longitudinal expansion of the lamp body which may occur during the use thereof is accommodated by the automatic displacement of that lamp cap which is engaged in the elongated recess 11 of the block 10.

I claim:—

1. A reflector for use with elongated, tubular electric lamps having lateral contacts adjacent each end, the reflector being formed to provide a longitudinally extending channel in its bottom adapted to receive sockets and having outwardly flaring reflecting surfaces on each side of the channel, and a plate detachably engaged with the channel and extending over the channel and forming a continuation of the outwardly flaring reflecting surfaces, said plate being apertured for the passage of lamp bases.

2. A reflector for elongated, tubular electric lamps having lateral contacts adjacent each end, the reflector comprising a longitudinally extending channel portion and outwardly flaring reflecting portions on each side of the channel portion, the walls of the channel portion adjacent the reflecting portions being outwardly offset, and a plate flanged at its margins, the flanges being adapted to be inserted in the outwardly offset portions of the channel, the face of the plate being approximately flush with the adjacent margins of the reflecting portions, the plate having apertures for the reception of lamp bases, the plate being detachably engaged with the wall of the channel.

In testimony whereof he has affixed his signature.

EDWIN RUDOLPH GROTE.
